UNITED STATES PATENT OFFICE.

DONALD B. MORISON, OF HARTLEPOOL, ENGLAND.

APPARATUS FOR CONDENSING STEAM.

1,378,553.

Specification of Letters Patent. Patented May 17, 1921.

Application filed December 5, 1918. Serial No. 265,471.

To all whom it may concern:

Be it known that I, DONALD BARNS MORISON, a subject of the King of Great Britain, residing at Hartlepool, Durham, England, have invented certain new and useful Improvements in Apparatus for Condensing Steam, of which the following is a specification.

This invention relates to an improved apparatus for condensing steam.

With condensers working under variable load, for example an auxiliary condenser on shipboard in which the amount of steam to be condensed depends on the number of auxiliary engines in use, the temperature of the condensate varies considerably with variations in the quantity of steam condensed. In condensers of this kind, whether worked at atmospheric pressure or under vacuum, it is usual to circulate such a quantity of condensing water that at the maximum or peak load the temperature of condensate will not exceed the desired predetermined high limit which can be satisfactorily dealt with by the discharging pump, the temperature of the condensate falling with reductions in the steam load, until at light load it is very considerably below the high limit desired.

Condensers have been proposed so designed that a proportion of the condensate collects in the bottom of the condenser and is cooled by contact with the condensing tubes or surface but in such cases the depth if immersion has been constant and controlled by the height at which the overflow opening was located or set. Obviously with such an arrangement the depth of cooling surface immersed would be, for a given setting of the overflow opening, the same for light loads as for heavy loads.

The object of my invention is to provide means whereby the cooling effect will vary automatically with the steam load and I accomplish this by causing the depth of condensing surface immersed to vary with the steam load.

That is to say at any given predetermined steam load practically all the condensate will flow away freely and there will be no cooling but as the steam load increases the condensate will collect and the depth of immersion will consequently increase. Thus a

more constant temperature of condensate will be attained since the cooling effect will increase automatically with the steam load. 55

My invention may therefore be said to consist broadly of a method of working steam condensers according to which, above any predetermined steam load, variations of steam load are accompanied by variations in 60 the condensing surface immersed.

The automatic means for cooling may be constructed integral with the condenser, or separate therefrom, but I prefer an arrangement in which the condenser is constructed 65 so that when the condensate is small in quantity it passes through an opening direct to the hotwell or the discharging pump, the opening being of such area that at higher loads, the condensate automatically rises in 70 the condenser, and floods over a portion of the condensing surface and is thereby cooled.

A convenient form of condenser constructed in accordance with my invention is illustrated in the accompanying drawings, 75 wherein Figure 1 is an elevational view of one form of condenser constructed in accordance with my invention, Fig. 2 is a sectional view thereof on line 2-2 of Fig. 1, and Figs. 3 and 4 are similar views illustrating my invention as applied to condensers of other well known forms. Referring to these drawings, and in particular to Figs. 1 and 2, the body 1 of the condenser is divided by vertical partitions 2 into a number of communicating condensing compartments 3 arranged in series in a known manner. According to my invention, however, I provide in the base of the condenser an outlet 4 (or more than one outlet may be 90 provided if desired), which is of the required area, or is fitted with means, as by a valve 5, whereby the area can be adjusted to requirements, and I arrange an overflow outlet or outlets 6 from the condenser 1, at a 95 suitable location above the bottom thereof. With such an arrangement, the condensate at a predetermined load flows from the condenser through the outlet or outlets 4 in the base, while as the load increases and the 100 condensate becomes greater in quantity, it gradually rises in the condenser by reason of its inability to flow sufficiently rapidly through the restricted outlet or outlets 4, and

floods over such of the condensing tubes 7 as are located below the overflow outlet or outlets 6, until at peak or maximum load, it reaches the overflow outlet 6 through which 5 it flows into a hotwell 8, and, mixing with the condensate flowing through the outlet or outlets 4 in the base, results in a supply which is not greater in temperature than desired. This arrangement is particularly useful 10 on shipboard, as when the exhaust from the auxiliary machinery is variable in quantity, the temperature of the condensate is automatically regulated in a simple manner to a temperature which is reasonably constant 15 but not excessive.

The arrangement described in Figs. 1 and 2 also has the advantage that by flooding the bottom of two or more of the compartments the area of the port or passage available for 20 the flow of steam from one compartment to another, may be reduced until only a narrow space is left between the edge of the partition and the surface of the water, thus tending to produce uniform distribution of steam 25 from one compartment to another throughout the length of such compartments.

In Figs. 3 and 4 my invention is shown as applied to other well known forms of surface condenser, and the principle of operation is in these cases precisely the same. The condenser 1 is provided with an outlet or outlets 4, whose effective area—which may be controlled by a valve such as 5—suffices 30 to drain away a predetermined quantity of condensate. An overflow outlet or outlets 6 preferably arranged beneath a baffle 9, which forces steam to follow a circuitous path are also provided together with the usual hotwell 8. The operation is precisely 35 as before described with reference to Figs. 1 and 2. That is to say, at any predetermined load all the condensate flows directly through this restricted opening which is insufficient to permit of the passage 40 of all the condensate when the load increases, and it therefore collects in the bottom of the condenser 1, the level rising until it flows through the overflow outlets 6, becoming sufficiently cooled by reason of its 45 contact with the lower condenser tubes.

Condensers in accordance with my invention may be supplied with the usual mountings and accessories.

What I claim and desire to secure by 50 Letters Patent is:—

1. A steam condenser having a restricted outlet proceeding from its base and means for controlling said outlet whereby at any predetermined steam load, determined by 55 the setting of the controlling means for the outlet, the condensate can flow away freely and be uncooled but as the steam load increases beyond the predetermined load condensate will collect in the bottom of the con-

denser and be cooled by the immersed condenser surface, increasing steam load being automatically accompanied by increasing depth of immersion of condenser surface. 65

2. A steam condenser having an outlet, means for regulating and controlling the effective area of said outlet, and an overflow outlet at a higher level, substantially as and for the purpose specified. 70

3. A steam condenser having an outlet, a screw down valve for regulating and controlling the effective area of said outlet, and an overflow outlet at a higher level, substantially as and for the purpose specified. 75

4. A steam condenser comprising a main condenser structure, a restricted outlet in the base of said structure, an overflow outlet from said structure at a higher level, and a hotwell into which both said outlets lead, substantially as specified. 80

5. A steam condenser having an outlet in its base, means for regulating and controlling the effective area of said outlet, and an overflow outlet at a higher level, and a hotwell into which condensate from both said outlets flows, substantially as specified. 85 90

6. A steam condenser having an outlet in its base, means for regulating and controlling the effective area of said outlet, and an overflow outlet at a higher level, and a hotwell into which condensate from both said outlets flows, substantially as specified. 95

7. A steam condenser having an outlet in its base, means for regulating and controlling the effective area of said outlet, an overflow outlet at a higher level, and a baffle located above said overflow outlet, substantially as and for the purpose specified. 100

8. A steam condenser having an outlet in its base, a screw down valve for regulating and controlling the effective area of said outlet, an overflow outlet at a higher level, and a baffle located above said overflow outlet, substantially as and for the purpose specified. 105

9. A steam condenser comprising a main condenser structure, a restricted outlet in the base of said structure, an overflow outlet from said structure at a higher level, a baffle located above said overflow outlet, and a hotwell into which both said outlets lead, substantially as specified. 110 115

10. A steam condenser having an outlet in its base, means for regulating and controlling the effective area of said outlet, an overflow outlet at a higher level, a baffle located above said overflow outlet, and a hotwell into which condensate from the condenser flows, substantially as specified. 120

11. A steam condenser having an outlet in its base, means for regulating and controlling the effective area of said outlet, and an overflow outlet at a higher level, a baffle located above said overflow outlet, and a 125

hotwell into which condensate from the condenser flows, substantially as specified.

12. A steam condenser having a restricted outlet and means permitting varying discharge therethrough whereby the depth of tube immersion increases with the increase of the steam load.

13. A steam condenser having an outlet, means for regulating and controlling the discharge from said outlet and an overflow

for determining the maximum depth of tube immersion.

Signed at American consular agency, West Hartlepool, England, this twentieth day of November, 1918.
